(57) **CLAIM**

The ornamental design for a housing for a display panel of a road construction machine, as shown and described.

DESCRIPTION

FIG. 1 is a top perspective view of a top cover of a housing for a display panel of a road construction machine showing my new design, the top cover shown removed for ease of illustration,

FIG. 2 is a top plan view,

FIG. 3 is a bottom plan view,

FIG. 4 is a front elevational view of FIG. 2,

FIG. 5 is a rear elevational view of FIG. 3,

FIG. 6 is a side elevational view of FIG. 3,

FIG. 7 is an opposite side elevational view of FIG. 3,

FIG. 8 is a top perspective view of a bottom part of a housing for a display panel of a road construction machine showing my new design, the bottom part shown removed for ease of illustration,

FIG. 9 is a top plan view of FIG. 8,

FIG. 10 is a bottom plan view of FIG. 8,

FIG. 11 is a side elevational view of FIG. 10,

FIG. 12 is an opposite side elevational view of FIG. 10,

FIG. 13 is a bottom elevational view of FIG. 10,

FIG. 14 is a top elevational view of FIG. 10.,

FIG. 15 is a top perspective view of a housing for a display panel of a road construction machine showing my new design, the top cover and bottom part shown in assembled condition,

FIG. 16 is a top plan view of FIG. 15,

FIG. 17 is a bottom plan view of FIG. 15,

FIG. 18 is a bottom elevational view of FIG. 17,

FIG. 19 is a top elevational view of FIG. 17,

FIG. 20 is a side elevational view of FIG. 17; and,

FIG. 21 is an opposite side elevational view of FIG. 17.
